UNITED STATES PATENT OFFICE.

LUDWIG SCHMIDT, OF ST. LOUIS, MISSOURI, ASSIGNOR TO ESSMUELLER MILL FURNISHING COMPANY, OF ST. LOUIS, MISSOURI, A CORPORATION OF MISSOURI.

GRINDING ROLL FOR FLOUR MILLS.

Application filed May 7, 1924. Serial No. 711,697.

To all whom it may concern:

Be it known that I, LUDWIG SCHMIDT, a citizen of the United States, residing in the city of St. Louis and State of Missouri, have ⁵ invented new and useful Improvements in Grinding Rolls for Flour Mills, of which the following is a specification.

This invention relates to grinding rolls for use in grinding cereals and particularly ¹⁰ in reducing wheat to flour, and in such use, is especially applicable to the gradual reduction of middlings.

The invention has for its general object ¹⁵ to provide an improved grinding or reducing surface on such a roll.

In effect, my invention is an improvement over the character of grinding roll described and claimed in my pending application Ser. No. 645,169, filed June 12, 1923, ²⁰ and is characterized by the fact that the lines are substantially straight in place of curvilinear and have a direction of extension longitudinal of the roll and diagonal to the axial line thereof, the general effect ²⁵ being that of a surface provided with lines of scratches presenting a substantially spiral formation. This statement, however, is subject to the modification that the lines are not continuous in extent from one end ³⁰ of the cylinder or roll to the other, but are multifrom as regards the longitudinal extension of the roll as well as with regard to the circumferential extension of the roll.

In the reduction of wheat to flour, corrugated rolls are employed in reducing the grain down to a certain stage in which middlings are produced, the corrugated rolls being usually referred to as the "break rolls". The middlings are composed of the ³⁵ hard granular portion of the grain, and the finer grades of flour are made from them. In their reduction, smooth rolls and finely corrugated rolls are employed.

The ordinary arrangement of grinding or ⁴⁰ reducing rolls involves two rolls set in close proximity to each other, one of the rolls being run at a slightly increased speed relative to the other.

Originally, in the reduction of middlings, ⁴⁵ smooth and highly polished rolls were employed. It was soon found, however, that notwithstanding the differential rate of speed at which the rolls were run, the broken particles of grain did not pass readily between the rolls, as the latter were too

smooth to bite or engage the particles of grain and cause them to pass between the rolls.

To overcome this disadvantage, rolls having very fine corrugations were substituted ⁶⁰ for the smooth rolls, at least at the head of the middlings reduction system. Not only are the finest practicable corrugations in such a roll too coarse to reduce the middlings in the manner desired, but it has been found to be ⁶⁵ almost impossible to secure accurate or uniform corrugation of the roll, due to mechanical reasons not necessary to set forth here.

To obviate the use of finely corrugated rolls, a method was devised for producing ⁷⁰ rolls with a dull finish instead of the highly polished surface which had previously characterized the smooth roll. The dull finish roll has been very extensively used, and, while it is an improvement over the polished roll, or the corrugated roll, it still presents the objection of being too smooth to cause the proper engagement and feed of the grain particles between the rolls. This is, ⁷⁵ to some extent, due to the fact that in producing the dull finish, such slight roughening of the surface as is caused by the emery wheel is along lines extending circumferentially of the roll, and hence only a slight increase in the gripping action of the roll is ⁸⁰ afforded.

According to the present invention, I provide for imparting a uniform degree of scratching on the surface of the roll, the scratched lines, as their name implies, being ⁹⁰ actually cut into the surface of the roll and extending substantially longitudinally thereof, so that while the surface of the roll is much rougher than that of a roll with a dull finish, such surface is much smoother ⁹⁵ than that of a roll having the finest degree of corrugation, which it has been found practicable to produce. At the same time, however, I secure all of the advantages of the corrugated roll without any of the disadvantages, by reason of the fact that I secure the necessary gripping action on the particles of grain, and abrasion, or attrition, ¹⁰⁰ thereof due to the substantially straight character and longitudinal extension of the ¹⁰⁵ scratched lines.

A further advantage of a roll produced according to my invention is the fact that the surface of the roll can be made almost, absolutely true or even, approaching abso- ¹¹⁰

lute accuracy more nearly even than a polished roll and to far greater extent than a corrugated roll, with the result that the flour produced in the use of these rolls is

5 characterized by uniform granulation, a highly desirable result in the milling art.

In practicing my invention, the surface of the roll is first smoothed off by an emery wheel in the usual manner. Thereafter, I 10 apply to the surface of the roll the side of an annular grinding wheel, the point of application being substantially at the termination of the horizontal diameter of the roll. The roll is then revolved, and the 15 grinding wheel in contact with the surface of the roll is also simultaneously revolved and moved endwise of the roll, with the result that with repeated travails of the grinding wheel from one end to the other 20 of the roll, the entire surface thereof is subjected to the abrasive or grinding action of the wheel. The size of the grinding wheel and the differential between its speed of rotation and the speed of rotation of the 25 roll are such that the grinding of the surface of the roll will be in substantially straight lines having, however, a diagonal or spiral extension on the cylinder. The surface of the roll will, by this means, be 30 scratched in a uniform manner, and the coarseness of the abrasions produced on the surface of the roll will correspond to the coarseness of the grain of the material of the grinding wheel.

35 Such method of scratching the surface of the roll possesses the advantages that it may be performed with relative rapidity, and the surface of the roll will be uniform throughout, as the latter is not subjected to 40 a bending pressure, as is the case where it is attempted to corrugate. Furthermore, not only are the scratched lines of uniform depth, but as the relative positions of the roll and grinding wheel are fixed during 45 the operation, and as the relative rates of movement of the grinding wheel and roll, and the speed at which the grinding wheel is advanced longitudinally of the roll, are unchanged during the operation, it follows 50 that the lines formed by the abrading points of the grinding wheel are produced with exact uniformity throughout the whole operation.

In order that the invention may be fully 55 understood, I have illustrated in the accompanying drawings an arrangement of apparatus by means of which the surface of a grinding roll may be scratched in a manner herein described. In said drawings—

Figure 1 is a cross-sectional view through a grinding machine provided with the means which I employ for practicing my improved method of finishing the surface of a roll;

60 Figure 2 is a view in broken elevation of

a grinding roll showing one end portion thereof provided with scratched lines in the manner effected by practicing the method which I employ; and

Figure 3 is a view on an enlarged scale 70 of the scratched surface shown in Figure 2.

It may be stated that Figures 2 and 3 were prepared from enlarged photographs of the surface of a roll finished according to my invention, but the draftsman has 75 found it practically impossible to exactly reproduce the effect. It is believed, however, that Figures 2 and 3 sufficiently bring out the salient feature of the invention, 80 namely, that the scratched lines are substantially straight and have a diagonal extension relative to the axis of the roll, although, owing to the curvature of the roll, they present the appearance of a spiral 85 formation.

Referring now to the drawing, the numeral 1 indicates the upper portion of a grinding machine, having heads 2, on which a grinding roll 3 may be rotatably supported. Mounted on the bed of this grinding machine is a carriage 4, which supports a motor 5, the shaft of which drives, through a belt 6, an annular grinding wheel 7. Means for producing longitudinal movement of the carriage 4 relative to the roll 3 and the means for rotating the roll are 90 not shown, as they are of the usual, or any preferred, construction.

In the apparatus illustrated in my pending application referred to above, the grinding disk I use was relatively small and the lines, while having a general longitudinal extension, were nevertheless of curvilinear form and, therefore, intersected each other so that there was a billowy or wave-like 100 effect produced indicating that the lines of scratching were not continuous. To overcome this objection or, rather, to increase the beneficial action afforded by the scratched roll of my prior application, 105 whereby lines of scratching may be made substantially straight and continuous in their extent, that is, without intersecting other lines in a circumferential direction, I employ the arrangement shown in the drawing, in which a grinding wheel or annulus 110 is substituted for the disk of the application and the diameter of this wheel is considerably greater than that of the disk which I previously employed. This grinding wheel, 115 furthermore, is provided with a beveled side indicated at 8, and said beveled side is applied to the surface of the roll at the bottom side of the grinding wheel, which grinding wheel, as viewed from the right in 120 Figure 1, is rotated in a counter-clockwise direction while maintained in a vertical position. As viewed in the drawing, the roll 3 is also rotated in a counter-clockwise 125 direction. The larger diameter of the grind-

120

ing wheel 8 as compared with the grinding disk of my prior application, its vertical position and its manner of application to the surface of the grinding roll, combined 5 with the desired differential of speed between the grinding wheel and roll, are the principal factors enabling me to produce lines of scratching on the surface of the roll, which are substantially straight and 10 continuous.

As will be understood by those skilled in the art, variations in the form and extension of the scratched lines can be readily effected in various ways, as by changing 15 the selected differential between the speed of the roll and grinding wheel, by changing the inclination of the grinding wheel, by changing the selected speed of movement of the grinding wheel longitudinally of the 20 roll, and the like. I conceive all such variations to come within the scope of the broad idea of the invention as claimed in my aforesaid pending application.

The present application is directed to the 25 specific embodiment of my invention in which the lines of etching or scratching are substantially straight and continuous, or free from intersection with other lines.

The grinding wheel 7 is preferably made 30 of carborundum, and where a maximum coarseness in the scratching is desired, the carborundum will be of correspondingly coarse grain. If a less degree of coarseness 35 of finish is desired, the grain of the carborundum wheel employed would be correspondingly less coarse.

Grinding rolls constructed according to 40 my invention have, in actual demonstration, shown increased capacity, cooler grinding, the production of a whiter, more uniform and stronger flour, and one having a slightly less ash content as compared with the action of smooth rolls. As compared with corrugated rolls, they require less power, a lower 45 maintenance cost, have a longer life, and produce decided improvements in the char-

acter of the flour as respects such qualities as whiteness, uniformity, granulation, strength, bloom, lowness of ash content, and the like.

50

I claim:

1. A roll for milling wheat having its entire surface scratched along substantially straight distinct lines of relatively short length having a general extension longitudinal of the roll.

55

2. A roll for milling wheat having its entire surface scratched along substantially straight distinct lines of irregular length having a general extension longitudinal of the roll.

60

3. A roll for milling wheat having its entire surface scratched along substantially straight lines of relatively short length and irregular arrangement and having a general extension longitudinal of the roll.

65

4. A roll for milling wheat having its entire surface ground-scratched along substantially straight lines of relatively short length and having a general extension longitudinal of the roll.

70

5. A roll for milling wheat having its entire surface ground-scratched along substantially straight lines of relatively short length and having a general extension longitudinal of the roll but diagonally positioned thereon.

75

6. A roll for milling wheat having its entire surface ground-scratched along substantially straight lines having a general extension longitudinal of the roll, said lines of scratches being multiform both longitudinally and circumferentially of the roll.

80

7. A roll for milling wheat having its entire surface scratched along substantially straight lines of relatively short length and irregular arrangement presenting a spiral formation on the roll.

85

In testimony whereof, I have hereunto set my hand.

LUDWIG SCHMIDT.
